UNITED STATES PATENT OFFICE.

CHARLES SEARS FINNEY, OF ST. PAUL, MINNESOTA.

CAN-OPENER.

1,175,942.

Specification of Letters Patent. Patented Mar. 21, 1916.

Application filed March 21, 1914. Serial No. 822,251.

To all whom it may concern:

Be it known that I, CHARLES S. FINNEY, a citizen of the United States, residing at St. Paul, in the county of Ramsey and State 5 of Minnesota, have invented certain new and useful Improvements in Can-Openers, of which the following is a specification, reference being had therein to the accompanying drawing.

10 This invention relates to a can opener and especially to wire rips in which the opening device is adapted to be placed in position at the time the can is sealed and will thereby be held in an operative manner 15 upon the upper portion of the can.

Another object of this invention is the production of a can opener which is used in combination with metallic cans and is placed in position at the time the can is 20 sealed, thereby being held in a manner so as to easily rip the cap from the can when desired.

With these and other objects in view this invention consists of certain novel combinations, constructions and arrangements of parts as will be hereinafter fully described and claimed.

In the accompanying drawing:—Figure 1 is a perspective view of the upper portion 25 of the can showing the opening or ripping device in position. Fig. 2 is a top plan view of the assembled device. Fig. 3 is a section taken on the line 3—3 of Fig. 2 looking in direction of the arrows. Fig. 4 35 is a section taken on the line 4—4 of Fig. 2 looking in direction of the arrow. Fig. 5 is a detailed perspective view of the opener or wire rip.

Referring to the accompanying drawing 40 by numerals it will be seen that this can opener or wire rip is used in connection with metallic cans which comprise a body portion 1 having at their upper ends a depending portion 2 which extends to form the inwardly extending flange 3, this flange 3 terminating in an upwardly bent annular lip 4. This flange extends annularly around the upper portion of the can and extends at right angles to the body portion 1 of the can so as to be in a horizontal plane. For the purpose of sealing the upper portion of this can, the cap 5 having the annular depending lip 6 formed integral thereon is positioned so as to allow the lower edge of this lip to rest upon the flange 3. By referring particularly to Fig. 4 it will be no-

ticed that the lip 6 is greater in size than the height of the flange 4, and thereby will space the body of the cap 5 from the upper edge of the flange 4, and furthermore; it 60 will be noted that the cap 5 is of sufficient size to allow the lip 6 to be spaced at a distance from the upper face of the lip 4, thereby forming a receiving portion 7. This cap 5 is held in position upon the flange 3 65 by means of the solder or like material 8 which is poured upon the upper portion of the flange 3 as disclosed clearly in Figs. 2, 3 and 4 so as to allow the solder 8 to engage the outer portion of the rim 6 and the depending portion 2 of the flange 3 and rest upon the upper portion of the flange. Since the solder will adhere to these several portions of the flange and cap, the cap will be held in firm engagement with the flange 70 while the opening in the upper portion of the can will be efficiently sealed.

For the purpose of opening or ripping the cap 5 from engagement with the upper portion of the can there is provided a wire 80 rip which comprises a single strand of wire 9 which is positioned within the space 7 formed between the lip 4 and rim 6. This wire 9 may, of course, be formed in any desired shape but as herein disclosed it is circular and is provided with an off-set portion 10 having a finger 11 terminating in a handle portion 12.

When this device is assembled the circular rip wire 9 is positioned upon the upper 90 portion of the flange 3 so as to engage the annular lip 4. The cap 5 is then placed in position so as to allow the annular rim 6 thereof to incase the wire 9 and form a closure for the upper portion of the can body 95 1. The solder 8 is then poured upon the upper portion of the flange, thereby forming an efficient seal for the can. The off-set portion 10 of the ripping wire 9 extends through the outer portion of the cap 5 as 100 shown at 13 while the finger 11 will rest snugly upon the upper portion of the cap 5 and will be held in position by means of the flap 14 which is formed or held in any suitable manner upon the central portion of 105 the cap 5. In this manner the device will assume a very compact position for allowing the same to be placed in a very small place for shipment or storage without danger of the finger 11 or handle 12 being positioned in the way. When it is desired to 110 open the can the handle may be pulled from

engagement with the flap 14. By pulling the finger and handle to a vertical position as disclosed in dotted lines in Fig. 3 the ripping movement or opening of the can 5 may be started. By continued pulling upon the finger 11 the wire 9 will begin to lift or rip the cap 5 from engagement with the flange 3 and solder 8. Since the body portion of the cap 5 is positioned at a spaced 10 distance beyond the upper portion of the annular lip 4 sufficient room will be allowed for the operation of the wire 9 to pull or rip the cap from engagement with the solder without causing the lip 4 to be bent out of 15 position, owing to the fact that as the wire is pulled upwardly above the same and will move inwardly as disclosed in dotted lines in Fig. 4. The wire 9 will be positioned above the upper portion of the lip 4 and will 20 therefore lift or rip in its correct vertical position. When this device is used by forming the wide flange and having the cap 5 positioned at a spaced distance above the lip 4 after the cap has been lifted or ripped 25 from engagement with the upper portion of the can, the lip will remain in its correct position, thereby preventing dirt or refuse from dropping into the can and will allow the can to be again used for suitable 30 purposes, owing to the fact that in opening the can the cap will be lifted from the upper portion of the can without injuring the lip 4.

From the foregoing description it will be 35 seen that a simple and efficient seal has been produced for the upper portion of a can which is used in combination with an efficient rip wire whereby the cap may be easily lifted or ripped from the upper portion of

the can without injuring the retaining flange 40 and lip of the can body.

I claim:—

In a device of the class described, the combination with a can body having an integral inwardly extending flange formed 45 at a spaced distance from the upper portion thereof and terminating in an annular upwardly extending lip, a rip wire carried by said flange and bearing upon said annular lip, a cap having a depending annular rim 50 positioned over said lip and said wire, said rim being of a greater height than said lip whereby the body portion of said cap will be held at a spaced distance above said lip and said wire, whereby said cap will form 55 an efficient closure for said can without interference from said wire, said wire extending outwardly through said cap, and a filler means carried by the outer portions of said flange upon the outer portion of said rim 60 of said cap whereby a seal will be formed for said cap and can body, said rim being adapted to protect said wire from said filler means, said wire being adapted to be pulled so as to move upwardly into engagement 65 with the body portion of said cap adjacent the upper portion of said rim and above said lip whereby when said cap is being ripped from said can the wire will not injure said lip whereby said lip will remain intact and 70 prevent the passage of refuse into said can body.

In testimony whereof I hereunto affix my signature in presence of two witnesses.

CHARLES SEARS FINNEY.
